FLOOR POLISHER

Michael C. Sawchuk, Toronto, Ontario, Canada

Application March 7, 1949, Serial No. 1,261
In Canada October 13, 1948

Term of patent 7 years

Cl. D9—2)

To all whom it may concern:

Be it known that I, Michael C. Sawchuk, a citizen of the Dominion of Canada, residing at 107 Front Street East, in the city of Toronto, in the county of York, in the Province of Ontario, Dominion of Canada, have invented a new, original, and ornamental Design for Floor Polishers, of which the following is a specification, reference being had to the accompanying drawing, forming part thereof.

In the drawings:

I claim:

The ornamental design for a floor polisher, substantially as shown.

MICHAEL C. SAWCHUK.
